VENDING MACHINE

Jose Arturo Conde, Independence, Mo., assignor to The Vendo Company, Kansas City, Mo., a corporation of Missouri

Filed Nov. 17, 1966, Ser. No. 4,717

Term of patent 14 years

(Cl. D52—3)

The figure is a front perspective view of a vending machine;

The side opposite to that shown is the same in appearance as that shown and the top, rear and bottom are plain in appearance. The series of spaced horizontal lines at the bottom left of the housing are intended to represent ornamentation.

I claim:

The ornamental design for a vending machine, as shown and described.
